UNITED STATES PATENT OFFICE

96,815

DESIGN FOR A LIQUID DISPENSING RACK OR THE LIKE

Cornelius Chambers, Birmingham, England

Application May 2, 1935, Serial No. 56,662

Term of patent 14 years

To all whom it may concern:

Be it known that I, Cornelius Chambers, a subject of the King of Great Britain and residing at Birmingham, England, have invented a new, original, and ornamental Design for a Liquid Dispensing Rack or the like, of which the following is a specification, reference being had to the accompanying drawing, forming part thereof, and in which,

Fig. 1 is a front elevational view of the liquid dispensing rack, showing my design.

Fig. 2 is a side elevational view.

Fig. 3 is a top plan view.

The present design shows a rack construction having two side standards and a lower cross bar support on said standards which carries a series

of dispensing taps having handles at their upper ends, downwardly directed outlet openings at their lower ends and oval or convex glass fronts.

At the top of the taps are located a series of corks or stopper members to receive a plurality of inverted bottles.

Another and upper cross member is provided extending between the standards having ring members to support the inverted bottoms of the bottles.

I claim:—

The ornamental design for a liquid dispensing rack or the like, substantially as shown and described.

CORNELIUS CHAMBERS.
